CUP DISPENSER

Samuel N. Hope, Wauwatosa, Wis., assignor to
Griffith-Hope Company, West Allis, Wis., a cor-
poration of Wisconsin

Application February 14, 1935, Serial No. 6,432

5 Claims. (Cl. 312—43)

The invention relates to dispensers for paper cups and the like.

It is desirable in many instances to dispense nested paper cups directly from the package in which they are supplied.

5 An object of the invention is to provide an improved dispenser for this purpose of simple, durable and inexpensive construction, and of such character as to facilitate the mounting therein of the cup package.

10 The invention further consists in the several features hereinafter described and claimed.

In the accompanying drawing, which illustrates one specific embodiment of the invention,

15 Fig. 1 is a perspective view of a cup dispenser constructed in accordance with the invention, a cup package being mounted in place;

Fig. 2 is a bottom view of the dispenser, parts being broken away and parts being shown in section, and

20 Fig. 3 is a front view of the dispenser, parts being broken away and parts being shown in section.

In the drawing, 10 designates a cardboard cup package or carton of a well-known type enclosing therein a stack of nested paper cups 11. The package is here shown to be of the usual square cross-section and bears suitable advertising and other indicia on one or more of its sides. By opening the bottom end of the package, cups 11 may be manually withdrawn one at the time bottom end foremost without danger of contaminating the rim portions of the cups.

It is desirable to provide means for holding the cup package and for insuring proper dispensing of the cups. In the present instance, the package is mounted in a holder 12 which consists of a sheet metal band or plate bent to C-shaped form and having a vertical rear wall 13, opposite flat vertical side walls 14, and a front wall which preferably is formed by spaced inturned vertical front flanges 15 on the side walls. The side walls may be either resilient or rigid, as desired. The rear wall 13 has a central vertical rearwardly projecting channel portion 16 provided with openings 17 to receive screws 18 or other fastening elements by which the holder is secured to any suitable support 19. The holder 12 is open at its upper and lower ends.

45 The package 10 slidably fits in the holder and is supported at its lower edge by stop lugs 20 bent from the rear wall 13.

50 In order to prevent the cups from falling out of the package and to insure proper dispensing of the cups, cam-forming embossments or pro-

jections 21 are pressed into the lower central portions of the holder side walls 14 and have a wedging engagement with the resilient opposite side walls of the cup package to bow or deflect the lower portions of these package walls inwardly, thereby pressing against and slightly deforming the cups, which are also resilient. The weight of the stack of cups is insufficient to overcome this frictional engagement, although the lowermost cup can readily be withdrawn by exerting thereon a slight downward pull.

55 When a cup package is to be mounted in dispensing position, the bottom end of the package is either unfolded or torn off and the package is pushed downwardly into the holder until the package rests on the lugs 20. During the insertion of the package, the cups are held from falling out in any suitable manner, as by the fingers of one hand while the package is held in the other hand, the cup-holding fingers being free to pass downwardly through the open front of the holder. When the package approaches its lowermost position, the opposite side walls of the package slidably and frictionally engage the cam embossments 21 and are thus bowed inwardly, as seen in Figs. 1 and 3, to engage and hold the lowermost cups against dropping out. In some instances, the bottom of the package may be left closed until the package is mounted in the holder. While the package is preferably pushed downwardly into the holder to engage the lugs 20, the embossments 21 are capable of supporting the inserted package in dispensing position with its lower edge spaced a short distance above the lugs.

60 When a cup is to be dispensed, it is given a slight downward pull to release it from the inwardly bowed side walls of the cup package, the succeeding cup being retained against dropping out by its engagement with these side walls. When the package is exhausted it is lifted out of the holder and discarded.

65 The front of the holder is preferably left open, as above described, in order to facilitate the insertion of the cup package, and to permit full display of indicia on the front panel of the package.

70 What I claim as new and desire to secure by Letters Patent is:

75 1. A dispenser for nested paper cups and the like, comprising a bent sheet metal plate forming a rear wall and opposite side walls and inturned front flanges on said side walls, said walls and flanges forming a holder into which a bottom-opening cup package is insertable, there being a

stop projection on said plate limiting the inserting movement of the package, and said opposite side walls each having a cam embossment engageable by the entering package for urging opposite lower side portions of the package into frictional engagement with the lower cups.

2. A dispenser for nested paper cups and the like, comprising a holder into which a bottom-opening cup package is insertable and having a wedging portion slidably engageable with the entering package for deflecting a lower side portion of the package inwardly into frictional engagement with the lower cups, and stop means for limiting the movement of the package into the holder to insure a predetermined inward deflection of the lower side portion of the package by said wedging portion of the holder.

3. A holder for a package of nested paper cups or the like, said package having inwardly yieldable resilient side walls and having an open lower end through which said cups are withdrawable closed end first, said holder being adapted to have said cup package inserted therein lower end first and having a wedging portion slidably engageable by the entering package to deflect a lower side portion of the package inwardly into frictional engagement with the lower cups for supporting the stack of cups and for limiting the withdrawal of the cups to one at a time.

4. A holder for a package of nested paper cups or the like, said package having inwardly yieldable substantially flat opposite side walls and having an open lower end through which said cups are withdrawable closed end first, said holder being adapted to have said cup package inserted therein lower end first and having opposed wedging cam surfaces engageable by the opposite side walls of the entering package to deflect said side walls inwardly into frictional engagement with the lower cups for supporting the stack of cups and for limiting the withdrawal of the cups to one at a time.

5. A holder for a package of paper cups or the like, said package having inwardly yieldable resilient side walls and having an open lower end through which said cups are withdrawable closed end first, said holder being adapted to have said cup package inserted therein and having sheet metal package-guiding side walls with inwardly pressed cam embossments thereon slidably engageable by the side walls of the entering package to deflect said package walls inwardly into frictional engagement with the lower cups for supporting the stack of cups and for limiting the withdrawal of the cups to one at a time.

SAMUEL N. HOPE.
